UNITED STATES PATENT OFFICE.

MORTON HAVENS, JR., OF ALBANY, NEW YORK.

DESIGN FOR A BRANCH BOX FOR INSULATED ELECTRIC WIRES.

No. 39,707.

Specification for Design.

Patented Dec. 22, 1908.

Application filed February 16, 1906. Serial No. 301,511. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for Branch Boxes for Insulated Electric Wires.

In the accompanying drawing, Figure 1 is a perspective view of a branch box for insulated electric wires, embodying my design, and Fig. 2 is a perspective view of said branch box shown as inverted.

As shown my design embodies a short pipe-like section having between its ends an elongated transverse box-like portion carrying a cover plate upon one side which cover plate has a projection substantially in line with the pipe-like section. The box-like portion

has its side opposite the cover plate rounded in cross section and has rounded corners and ends, and it will be observed that the junction between the pipe-like section and box-like portion is formed by curves whereby one merges into the other. The cover plate has rounded ends conforming to the shape of the box-like portion. The relative size of the parts and the lines of curvature are such as to give to the device an ornamental and attractive appearance.

What I claim is:—

The ornamental design for a branch box for insulated electric wires, substantially as herein shown and described.

MORTON HAVENS, JR.
